DESIGN FOR A BOTTLE

Andre Sussman, New York, N. Y., assignor to Moneau Corp. of New York, New York, N. Y., a corporation of New York

Application August 22, 1945, Serial No. 121,573

Term of patent 14 years

(Cl. D58—8)

To all whom it may concern:

Be it known that I, Andre Sussman, a citizen of the United States, residing at New York city, in the county of New York and State of New York, have invented a new, original, and ornamental Design for a Bottle, of which the following is a specification, reference being had to the accompanying drawing, forming part thereof.

In the drawing:

Fig. 1 is a perspective view of a bottle showing my new design.

Fig. 2 is a top plan view thereof.

Fig. 3 is a bottom plan view.

Fig. 4 is a side view of the stopper member.

Fig. 5 is a bottom view of said stopper member.

I claim:

The ornamental design for a bottle, substantially as shown.

ANDRE SUSSMAN.
